MAGNETRON

Hans Erich Hollmann, Berlin, Germany, assignor
to Telefunken Gesellschaft für Drahtlose Tele-
graphie m. b. H., Berlin, Germany, a corpora-
tion of Germany

Application September 8, 1938, Serial No. 228,908
In Germany August 24, 1937

5 Claims. (Cl. 250—27.5)

My invention relates to electron discharge de-
vices of the magnetron type, in which the elec-
trode system is positioned within a magnetic field.

In the operation of the conventional magne-
tron comprising an axial hot cathode and a
cylindrical anode surrounding the cathode con-
centrically and consisting of a solid piece or split
into a plurality of segments, it has frequently
been observed that an abrupt rise of emission
10 current occurs when the critical intensity of the
magnetic field is approached or upon initiation
of oscillations. The sudden rise of emission cur-
rent is due to an additional or extra heating of
the filament, in fact, this is readily discernible
15 not only by a visible increase in the brightness,
but also by a drop in the heating current oc-
casioned by the incidental rise in the resistance
of the filament. Under certain circumstances,
the emission may gradually rise to such a point
20 that the tube is caused to explode as a result of
overload. Particularly where insufficiently evac-
uated tubes are concerned, or tubes exhibiting a
tendency towards a sudden liberation of gases,
the additional heating or extra heating effect is
25 dangerous, and this seems to indicate that the re-
heating is caused by bombardment of the cathode
by gas ions. Another cause for such sudden re-
heating resides in the bombardment of the cathode
by electrons returning to the cathode, a phe-
30 nomenon which happens especially during the
optimum working state of the tube, in other
words, at a time when the energy yield is partic-
ularly great. It is known from practice that
such extra heating effects in the case of oxide
35 cathodes grow to proportions so that the use of
cathodes of this kind is not feasible.

Various ways and means have been attempted
in the past to either eliminate or suppress such
extra heating effects and their disturbing actions
40 either entirely or else to at least diminish them.
For instance, an attempt has been made to link
the anode current of the tube with the magnetic
field by causing the same to flow through one of
the exciting coils. It has thus been feasible to
45 meet a sudden and unexpected rise of the anode
current by a practically simultaneous re-inforce-
ment of the magnetic field. However, such a
cure of the evil means always in practice a de-
parture from optimum working conditions, in
50 fact, a magnetron arrangement utilizing the said
idea operates under impaired conditions of effi-
ciency. On the other hand, it has been sug-
gested in the recent art to preclude from the
outset all risk of re-heating or extra heating
55 by returning electrons by disposing the electron

source itself outside the anode cylinder, the elec-
trons being then attracted from the outside into
the anode cylinder. As a consequence, they will
never have a chance to fly back to the cathode,
indeed, they must always impinge upon the anode. 5

However, an arrangement of the cathode out-
side the anode cylinder is attended with the draw-
back that the distribution of the electrical field
is essentially altered compared with what it is in
the conventional magnetron tube of co-axial con- 10
struction, and such unfavorable field distribution
reacts disadvantageously upon the operation of
tubes having an outside cathode. 10

The principal object of my invention is to pro-
vide an improved type of electron discharge de- 15
vice of the magnetron type in which undesirable
heating by bombardment of the cathode by ions
or electrons is substantially eliminated, and yet
in which the distribution of the electrical field is
not detrimentally modified. 20

The present invention discloses effective ways
and means adapted to cure the undesirable heat-
ing evil by preserving the satisfactory concentric
electrode mounting with radial field lines existing
in the conventional type of magnetron, with this 25
difference that the portion of the cathode which
is located inside the cylindrical anode does not
emit electrons and is cold, whereas the source
proper of the electrons, that is to say, the heated
cathode itself is at one or both ends of the cold 30
cathode and lies on an extension of the axis of
the cold section of the cathode. In order that the
cold cathode may not be struck by returning
electrons and thus be caused to give off secondary
electrons, it will be found advantageous to im- 35
part to it a negative biasing potential with refer-
ence to the hot cathode so that reversing elec-
trons are no longer able to strike it squarely. 35

The novel features which I believe to be char-
acteristic of my invention are set forth with par-
ticularity in the appended claims, but the inven-
tion itself will best be understood by reference to
the following description taken in connection
with the accompanying drawing in which Figure 1 40
is a schematic section through one form of elec-
tron discharge device made according to my in-
vention and its associated circuit and Figure 2
shows a schematic section of a modification of an
electron discharge device made according to my 45
invention.

Referring to Figure 1, an envelope G contains
the cylindrical anode A which for the sake of
simplicity is here shown unsplit, though it will be
evident that the anode cylinder could just as well
comprise a plurality of segments. The hot cath- 50
55

- ode K is mounted outside the anode cylinder and extends in a direction along a prolongation of the axis of the tube. Now, according to the invention, adjacent the accelerator field directed 5 from the cathode towards the anode cylinder, a well defined radial field is created by providing along the axis a rod or tubular cold cathode K' which extends the full length of the anode cylinder, the cold cathode being kept either at the 10 potential of the real cathode or the heated cathode K or else is impressed with a negative biasing potential referred to the hot cathode. It can be readily understood that all electrons which are drawn from the accelerative field extending from 15 the heated cathode K to the anode cylinder into the space interiorly of the anode cylinder will, within the radial field between K' and A be subject to the same or to similar kinetic laws as in the conventional type of magnetron tube. 20 However, inasmuch as the paths of the electrons carried away from the heated cathode are spiraled, return of electrons to the heated cathode K is precluded and thus also the extra heating thereof is entirely avoided. 25 By choosing a suitable biasing potential for K' it is an easy matter to make conditions so that optimum working conditions are realized. On the other hand, the cold cathode K' could be used to act as a control electrode for the purpose of modulating, for instance, the magnetron oscillations, and this is accomplishable in the absence of energy dissipation since it does not absorb any electrons. 30 In order that in a similar way the axial field component may be reinforced and suitably balanced, cathode K is conveniently surrounded by a metallic cylinder of the nature of the well-known Wehnelt cylinder or else rearward shielding is provided by means of a negatively biased terminal disk E. Further amplification of the axial 35 field component, optionally, may be obtained by the aid of a terminal plate P which shuts the open end of the anode cylinder and which is kept at a positive potential. A coil M furnishes the magnetic field. 40 It will be understood that the basic idea underlying the present invention, namely, to divide the axial electrode into an electron-emissive part located outside the anode cylinder, and a central non-emissive portion is capable of a great many 45 modifications without departing from the fundamental idea of this invention. 50
- An exemplified embodiment of such modification is shown in Figure 2 in the form of a symmetric magnetron tube in which the heated cathodes properly so-called surround the axial, cold cathode in the shape of concentric or co-axial spirals. The anode cylinder A has along its axis the negatively biased cold cathode K' which, in this form of construction, extends at both ends 55 beyond the anode cylinder. The projecting ends are concentrically enveloped by spirally heated cathodes K₁ and K₂ at the two ends. As in the previous embodiment, both cathodes are shielded 60 outwardly, that is to say, towards the end away from the anode cylinder, by means of terminal disks E₁ and E₂ which are also negatively biased, the said terminal disks, if desired, being fitted 65 upon the axial electrode K'. If necessary, the discharge spaces for the two cathodes may be 70 separated by means of a radial disk or partition P mounted in the plane of symmetry. The action of the said partition disk is similar to the termi-

nal disk in Figure 1. It will be obvious that the rotations of electrons must be in opposite senses in the two spaces because of the fact that the electrical fields are of contrary directions.

While I have indicated the preferred embodiments of my invention of which I am now aware and have also indicated only one specific application for which my invention may be employed, it will be apparent that my invention is by no means limited to the exact forms illustrated or 10 the use indicated, but that many variations may be made in the particular structure used and the purpose for which it is employed without departing from the scope of my invention as set forth in the appended claims. 15

What I claim as new is—

1. An electron discharge device having an envelope containing a straight cold cathode, an anode surrounding said cathode and co-axial with said cathode, a thermionic cathode positioned adjacent one end but outside the space between said cold cathode and anode for supplying electrons to the space between said cathode and anode and lying along the axes of said cold cathode and anode and means for producing a 25 magnetic field parallel to and between the cold cathode and said anode.

2. An electron discharge device having an envelope containing a straight cold cathode, an anode surrounding and co-axial with said cold cathode, a thermionic cathode positioned adjacent one end and along the axis extended from said cathode and anode for supplying electrons to the space between said cold cathode and said anode and shielding means co-axial with said cold cathode and positioned outside of and adjacent the anode and the thermionic cathode. 35

3. An electron discharge device having an envelope containing a straight cold cathode, an anode surrounding and co-axial with said cold cathode, a thermionic cathode positioned adjacent one end and along the axis extended from said cathode and anode for supplying electrons to the space between said cold cathode and said anode and shielding means co-axial with said cold cathode and positioned outside of and adjacent the anode and the thermionic cathode, and a shield closing the other end of the anode. 45

4. An electron discharge device having an envelope containing a straight cold cathode, an anode co-axial with and surrounding said cathode, thermionic cathodes positioned adjacent each end of the anode and said cold cathode and co-axial with said cold cathode but outside of the space between said cathode and said anode, and shielding means adjacent each cathode outside of but adjacent said anode. 55

5. An electron discharge device having an envelope containing a straight cold cathode, an anode co-axial with and surrounding said cathode, thermionic cathodes positioned adjacent each end of the anode and said cold cathode and co-axial with said cold cathode but outside of the space between said cathode and said anode, and shielding means adjacent each thermionic cathode, and an electrode extending transversely of said cold cathode and anode and between said cold cathode and anode for confining electrons from each of said thermionic cathodes to the halves of the interior of said anode adjacent the respective 65 thermionic cathodes. 70
